CLAIM

The ornamental design for a soap dispenser, substantially as shown and described.

DESCRIPTION

FIG. 1 is a front, raised perspective view of a soap dispenser according to the invention;

FIG. 2 is a front view of the soap dispenser of FIG. 1;

FIG. 3 is a rear view of the soap dispenser of FIG. 1;

FIG. 4 is a right side view of the soap dispenser of FIG. 1;

FIG. 5 is a left side view of the soap dispenser of FIG. 1;

FIG. 6 is a top view of the soap dispenser of FIG. 1;

FIG. 7 is a bottom view of the soap dispenser of FIG. 1; and,

FIG. 8 is a front, lowered perspective view of the soap dispenser of FIG. 1.

The broken lines shown in the drawings form no part of the claimed design. All surfaces not shown form no part of the claimed design.
